(57) **CLAIM**

The ornamental design for a computer tablet holder and pen holder for a round storage ottoman lid, as shown and described.

DESCRIPTION

FIG. 1 is a perspective view of a round ottoman and lid constituting an environment for a computer tablet holder and pen holder;

FIG. 2 is a exploded side view of the computer tablet holder and pen holder attached to an underside of a lid of a round storage ottoman, the view from the side at other angles being identical;

FIG. 3 is a bottom view of the round ottoman constituting an environment for the computer tablet holder and pen holder; FIG. 4 is a top view of the round ottoman constituting an environment for the computer tablet holder and pen holder; FIG. 5 is a top view of the computer tablet holder and pen holder attached to the underside of the lid of the round ottoman constituting an environment for the computer tablet holder and pen holder;

FIG. 6 is a perspective view of the computer tablet holder and pen holder attached to the underside of the lid of the round ottoman constituting an environment for the computer tablet holder and pen holder;

FIG. 7 is a sectional view through the line 7'-7" in FIG. 6 of the computer tablet holder and pen holder attached to the underside of the lid of the round ottoman constituting an environment for the computer tablet holder and pen holder;

FIG. 8 is a bottom view of the computer tablet holder and pen holder; and,

FIG. 9 is a top view, with the lid removed, depicting the inside of the round ottoman constituting an environment for a computer tablet holder and pen holder.

The broken lines shown are for illustrative purposes only and form no part of the claimed design.
